UNITED STATES PATENT OFFICE

2,002,387

WELL DRILLING APPARATUS

Clyde E. Bannister, Houston, Tex.

Application June 1, 1933, Serial No. 673,798

18 Claims. (CL. 255—4)

This invention relates to apparatus for drilling wells in which a rotative bit is employed for dislodging the particles of earth or rock and a current of fluid is employed for washing the particles to the surface of the ground and preferably, although not necessarily, for driving the bit.

The chief objects of the invention are to provide economy of apparatus, to provide economy of power consumption, to provide economy of time, to provide economy of labor, to expedite the operations of pulling the drilling and fluid-circulating devices from the hole and lowering them thereinto as compared with the uncoupling and re-coupling of drill pipe, to provide economically and conveniently for dislodging a bit that has become stuck by reason of sedimentation or a cave-in or other cause, to provide in an improved manner for continuous deepening of the hole without interruption of operations and to provide other advantages which will be manifest in the study of the following description.

Of the accompanying drawings:

Fig. 1 is a vertical section of parts of a preferred embodiment of the invention.

Fig. 2 is a vertical section, on a smaller scale, of the portions of the apparatus next above those of Fig. 1.

Fig. 3 is a horizontal section on line 3—3 of Fig. 1.

Fig. 4 is a horizontal section on line 4—4 of Fig. 1.

Fig. 5 is a horizontal section on line 5—5 of Fig. 1.

Fig. 6 is a horizontal section on line 6—6 of Fig. 1.

Fig. 7 is a vertical section on line 7—7 of Fig. 1.

Fig. 8 is a vertical section of parts of a modification.

Referring to the drawings, the apparatus comprises a housing 10 connected through a vertical, axial supply pipe 11 (Fig. 2), a swivel 12, and a fluid-supply and guide pipe 13 with a hose 14 leading into the well and suitably manipulated and supported at the top of the well by reeling and supporting devices which are not shown but which are within the skill of the ordinary artisan to provide.

Slidably mounted upon the fluid-supply and guide pipe 13 for vertical movement thereon is a lost-motion jar-weight 15 (Fig. 2) adapted at the lower limit of its relative movement to abut the swivel 12 and at the upper limit of its relative movement to abut an annular flange 13a formed on or secured to the fluid-supply and guide pipe 13, the jar-weight 15 having secured therein a

pair of vertical supporting rods 16, 16 which are slidably mounted in apertures formed in the flange 13a and at their upper ends are connected to a pair of cables 17, 17 which at the top of the well are provided with suitable supporting and reeling devices (not shown) for lowering them into and reeling them out of the well and on occasion for imparting to them such quick vertical movement as to raise the jar-weight 15 from its lowermost position, against the swivel 12, or from any intermediate position, and cause it to abut the flange 13a with a heavy impact, to loosen the housing 10 and the bit carried thereby from any sedimentation or cave-in in which the bit or the bit and housing may have become stuck.

The cables 17 may be provided at intervals with means (not shown) for locally supporting the hose to avoid excessive strain on the latter.

The top end of the housing 10 is closed except for its communication with the supply pipe 11 and at its lower end is provided with a closure disc or floor 18 (Fig. 1) which is centrally formed with a bearing aperture for the hollow stem 19 of an outer bit 20, which stem accommodates other members mounted within it for relative rotation.

For supporting upon the outer bit 20 a proper part of the weight of the casing 10 and the parts associated therewith a ball thrust-bearing 21 is interposed between a bearing-race shoulder 22 formed on the closure disc 18 and a bearing-race shoulder 23 formed on the stem 19 of the outer bit 20, and lip-gaskets 24 and 25 are provided between the closure disc 18 and the stem 19, above and below the bearing, respectively, for preventing excessively coarse particles from gaining access to the bearing.

The upper end portion of the stem 19 lies within and is journaled in the upper and lower end walls of the casing 26 of a positive displacement, eccentric, rotary, fluid-pressure motor which is connected to the inner wall of the housing 10 by radial brackets 26a, 26b, and is adapted to receive driving fluid from the interior of the housing 10 through a motor inlet 27 and discharge it into an outlet pipe 28, the stem 19 having secured thereon a rotor 29 (Fig. 5) provided with rotary pistons 30, 30, here shown as of the pivoted and spring-backed type, for driving the outer bit 20, clockwise as viewed from above, as in Fig. 6.

An inner bit 31 adapted to be driven counter-clockwise, and approximately to counter-balance the reaction torque of the outer bit 20, is formed with a hollow stem 32 which extends upwardly through the hollow stem 19 of the outer bit 20

50

55

and at its upper end is provided with a swivel 33 connecting it in fluid-conducting communication with a pipe 34 centrally mounted in a spider 35 which is secured by screws 36, 36 to the inner 5 wall of the housing 10, a ball thrust-bearing 37 being interposed between the upper end of the stem 32 and the spider 35 to cause the inner bit 31 to support its proper part of the weight of the housing 10 and parts associated therewith.

10 The upper end portion of the stem 32 lies within and is journaled in the upper and lower end walls of the casing 38 of a positive-displacement, eccentric, rotary fluid pressure motor which is connected to the inner wall of the housing 10 by radial brackets 38^a, 38^b and is adapted to receive driving fluid from the exhaust of the motor casing 26 through a conduit comprising the pipe 28 and an inlet wing 38^b formed on the casing 38, the stem 32 having secured thereon, by means of an interposed build-up bushing 32^a, a rotor 39 (Fig. 3) provided with rotary pistons 40, 40, here shown as of the pivoted and spring-backed type, for driving the inner bit 31, counter-clockwise as viewed from above. The exhaust wing 41 of this motor (Fig. 3) is connected to a pipe 42 (Fig. 1) which leads, through a conduit 43 (Fig. 1) to the pipe 34, so that the water exhausted from the second of the two motors in series is conducted through the stem 32 of the inner bit 31 and discharged at the lower end of the bit assembly, preferably at the center thereof, for washing up to the top of the well, through the space provided by the greater diameter of the outer bit 20 as compared with the diameter of the housing 10, the particles dislodged from the bottom of the hole by the bits, the bit 20 being of two-arm or other spider construction so as to permit the necessary flow of the drilling fluid.

For stabilizing the assembly against any net torque resulting from imperfect balancing of the torque of the outer bit 20 against that of the inner bit 31, a concentric, annular anchor foot 44 is interposed between the two bits, is provided at its lower, annular margin with sharp projections 44^a, 44^b adapted to engage in the material of the bottom of the hole, and has a stem 45 which extends upwardly between and in concentric relation to the stems 19 and 32 of the bits and at its upper end (Fig. 1) is threaded into the hub of a spider 46 of which the arms are slidably mounted at their outer ends for vertical movement between the arms of respective U-shaped guide members 47, 47, the bases of the U-shaped guide members being adapted to serve as stops for the downward movement of the spider 46 and the anchor-foot 44 rigid therewith, and a helical compression spring 46^a is interposed between the bottom of the upper motor casing 38 and the hub of the spider 46 for urging the anchor-foot 44 downwardly toward a relative position such that its projections 44^a, 44^b will engage with the material of the bottom of the hole, whether the bits be in advance of or behind the said projections in the descent.

Preferably the stem 45 of the anchor foot 44 is faced with a rubber layer 48 on its outer face for water-lubricated contact with the inner face of the stem 19 of the outer bit 20 and with a layer of rubber 49 on its inner face for water-lubricated contact with the outer face of the stem 32 of the inner bit 31.

The hub of the spider 46 is shown as provided with a rubber lip-gasket 50 (Fig. 1) for sealing it to the stem 32 of the bit 31, and similar provision may be made for sealing the space between the upper end portion of the stem 45 of the anchor-

foot and the stem 19 of the outer bit 20, but such downward leakage as occurs between these several stems serves to produce a downward flow in the intervening spaces of comparatively non-abrasive fluid from the interior of the housing 10 and thus to prevent the migration of coarse particles from the region of the bits into the said spaces, and it is desirable to provide suitably for some such leakage in order to provide water-lubrication for the rubber coatings 48, 49.

Permissibly the two motors, although of the same structure in cross-section, may be of different axial lengths, as shown, to provide determinately different angular speeds for the two bits.

In the operation of the apparatus, the hose 14 and the cables 17 and the parts associated therewith as described are lowered and pressure fluid is supplied through the hose 14 to drive the motors, and consequently their respective bits, in opposite directions, which causes them to drill away the material of the bottom of the hole, and the exhaust fluid from the motors, discharged at the bottom face of the bit assembly, washes the cuttings up to the top of the well, where the fluid and the cuttings carried thereby are dealt with in the usual manner, the cuttings being settled out in the slush-pit and the fluid again circulated downward through the hose 14 and upward through the well on the exterior of the hose.

As the two motors are in series they are compelled to drive the bits in the predetermined ratio of angular speed, and excessive rotation of the housing 10 and twisting of the hose and cable assembly is prevented by the spring-backed anchor-foot 44. The annular space between the two bits, partially occupied by the anchor-foot 44, may be so narrow that the earth or rock between the two bits will be effectively chipped off by the eccentric or erratic horizontal impulses of the bit assembly.

The cables 17 during the drilling operation preferably are so slackened as to permit a substantial part or all of the weight of the housing 10 and parts mounted therein, and permissibly also that of the jar-weight 15, to be imposed upon the bits, and in case of the bits or housing becoming stuck the cables are rapidly raised, which causes the jar-weight to contact the flange 13^a of the pipe 13 with a strong impact, for loosening the assembly from the material in which it is stuck. The arrangement is such that an effective jar is provided without the necessity of the sliding packed joint which is required in ordinary rotary rigs as now employed.

In the modification shown in Fig. 8, a middle bit 52 and two outer bits 53, 53 are secured upon a horizontal shaft 54 which is journaled in a pair of brackets 55, 55 extending downward from a horizontal bulk-head 56 mounted in a housing 57, these bits being adapted to be driven in one direction, and two intermediate bits 58, 58, adapted to be driven in the opposite direction, are loosely-journaled upon the shaft 54, one on each side of the middle bit 52 and between it and the adjacent end bit 53, the bits of the assembly being so formed that in the aggregate they represent a substantially complete sphere, so as to drill a round hole although journaled on a horizontal axis.

For driving the bits without torque upon the housing 57 about a vertical axis a positive-displacement rotary fluid-pressure motor 59 is secured in the housing 57 between the bulk-head 56 and a higher bulk-head 60 and adapted to be supplied with pressure-fluid through an inlet pipe 61.

leading from a hose (not shown) such as the hose 14 of Fig. 2, and cables such as the cables of Fig. 2, and permissibly also the jar assembly of Fig. 2, may be provided.

5 The rotor shaft 62 of the motor has secured thereon a gear 63 which is meshed with a gear 64 mounted on a stub-shaft projecting from the motor casing and having as a twin on said shaft a bevel gear 65 meshed with a bevel gear 66 which 10 is secured on the upper end of a vertical shaft 67 journaled in the bulk-head 56 and provided with a pair of thrust-bearings acting against the bulk-head, one of which is shown at 68.

Below the bulk-head 56 the vertical shaft 67 has secured thereon two bevel gears 69, 70. The gear 69 is meshed with a gear 71 secured upon a horizontal shaft 72 which is journaled in the brackets 55, 55 and has secured on its other end a gear 73, the gears 71 and 73 being meshed respectively with sets of bevel gear teeth formed on the peripheries of the intermediate bits 58, 58. The bevel gear 70 is meshed with the bevel portions of a bevel-and-spur gear 74 freely journaled on the shaft 72, the spur portions of the teeth being meshed with a set of spur-gear teeth formed on the periphery of the middle bit 52.

The motor is adapted to discharge the driving fluid through a pipe 75 which extends with a sealing fit through the lower bulk-head 56 and is extended as a coil about the upper portion of the bit assembly, where it is provided with discharge apertures 76, 76 for discharging the pressure-fluid in the region of the bits for washing the cuttings to the top of the well.

35 The bulk-heads 60 and 56 are bevel-fitted to internal flanges on the housing 51, the upper bulk-head being the smaller in diameter, so that they may be introduced into the housing in succession from below and secured in place with a sealing fit, as by means of screws such as the screws 56^a, 60^a, 60^a, and the space between the bulk-heads, about the motor and adjacent gears, may be packed with grease.

45 In the operation of this embodiment the motor is continuously driven in the same direction by the motive fluid and the middle bit 52 and the end bits 53, 53 are thereby driven in one direction and the intermediate bits 58, 58 in the opposite direction, with substantially no torque of 50 the structure as a whole about a vertical axis, or only such erratic torque, incident to unequal resistances of the bits, as to cause occasional changes of orientation of the axis of the bits and thus chip out or cause cross-grinding of such ridges 55 of earth or rock as have been left temporarily in the spaces between the intermediate bits 58 and the middle bit 52.

The bit assembly has only such tendency to "walk" horizontally as is represented by unbalanced resistance of the bits and this is largely neutralized by the law of averages applying from moment to moment and also is resisted by contact of the housing 51 with the vertical walls of the hole, the housing being of such length as to have bearing points against the walls extensively spaced vertically from each other so as to prevent rapid departure of the drilling operation from a vertical direction.

Other modifications are possible within the 70 scope of my invention and I do not wholly limit my claims to the specific embodiments herein shown.

I claim:

1. Well drilling apparatus comprising at least 75 a pair of oppositely-rotating bits, a mounting

common to the bits, means for circulating a current of fluid to wash the cuttings of the bits to the top of the well, and means in the vicinity of the bits and driven by the said current of fluid for driving the bits.

2. Well drilling apparatus comprising a plurality of rotary bits, a mounting common to said bits, the bits being so arranged on said mounting as to impose upon said mounting less than the sum of their reaction torques, means for circulating a current of fluid to wash the cuttings to the top of the well, and means in the vicinity of the bits and driven by the said current of fluid for driving the bits.

3. Drilling apparatus comprising at least a pair of oppositely rotating bits, a mounting common to the bits, fluid actuated means for driving said bits in their opposite directions and discharging the fluid in the vicinity of the bits for washing the cuttings to the top of the well, and means in the vicinity of the bits for sustaining by contact with a surface formed by the drilling operation the net reaction torque of the bits.

4. Drilling apparatus comprising at least a pair of oppositely rotating bits, a mounting common to the bits, fluid actuated means for driving said bits in their opposite directions and discharging the fluid in the vicinity of the bits for washing the cuttings to the top of the well, and means in the vicinity of the bits for sustaining by contact with a surface formed by the drilling operation the net reaction torque of the bits, the bits being substantially coaxial.

5. Drilling apparatus comprising a plurality of rotary bits, a mounting common to the bits, fluid actuated means for driving the bits and discharging the fluid in the vicinity of the bits for washing the cuttings to the top of the well, and means for sustaining by contact with a surface formed by the drilling operation the net reaction torque of the bits.

6. Drilling apparatus comprising a plurality of rotary bits, a mounting common to the bits, fluid actuated means for driving the bits and discharging the fluid in the vicinity of the bits for washing the cuttings to the top of the well, and means for sustaining by contact with a surface formed by the drilling operation the net reaction torque of the bits, the bits being substantially coaxial.

7. Drilling apparatus comprising at least a pair of oppositely rotating bits, a mounting common to the bits, fluid-actuated means for driving said bits in their opposite directions and discharging the fluid in the vicinity of the bits for washing the cuttings to the top of the well, and means in the vicinity of the bits for sustaining by contact with a surface formed by the drilling operation the net reaction torque of the bits, the bits being so associated as temporarily to leave a ridge between the areas drilled by them and to chip the material from the ridge by erratic action.

8. Drilling apparatus comprising a plurality of rotary bits, a mounting common to the bits, fluid-actuated means for driving the bits and discharging the fluid adjacent the bits for washing the cuttings to the top of the well, and means for sustaining by contact with a surface formed by the drilling operation the net reaction torque of the bits, the bits being so associated as temporarily to leave a ridge between the areas drilled by them and to chip the material from the ridge by erratic action.

9. Drilling apparatus comprising at least a

pair of substantially coaxial rotary bits, a pair of substantially coaxial pressure-fluid motors for driving the bits in opposite directions, and means conducting the exhaust fluid from the motors to the vicinity of the bits for washing away the cuttings.

10. Drilling apparatus comprising at least a pair of substantially coaxial rotary bits, means for driving the bits in opposite directions, means for washing away the cuttings, and an anchor-foot in an annular space between the bits and adapted to contact the material being drilled for sustaining the net reaction torque of the bits.

15. pair of substantially coaxial rotary bits, means for driving the bits in opposite directions, means for washing away the cuttings, and a spring-backed anchor-foot in an annular space between the bits and adapted to contact the material being drilled

20 for sustaining the net reaction torque of the bits.

12. Drilling apparatus comprising at least a pair of substantially coaxial rotary bits, a pair of substantially coaxial pressure-fluid motors for driving the bits in opposite directions, the said apparatus having provision for discharging the fluid from the motors in the vicinity of the bits for washing away the cuttings.

13. Drilling apparatus comprising a plurality of rotary bits and a plurality of positive-displacement pressure-fluid motors mounted in series for actuation by the same current of fluid passing through them in succession and of different piston displacement for driving respective bits at determinately different angular speeds.

35 14. Drilling apparatus comprising a plurality of rotary bits and a plurality of positive-displacement pressure-fluid motors mounted in series for actuation by the same current of fluid passing through them in succession and of different piston displacement for driving respective bits at determinately different angular speeds, the motors being of like construction except that they are of

different axial length for providing the different piston displacements.

15. Drilling apparatus comprising a bit, bit driving means, means for conducting fluid to the vicinity of the bit and there discharging it for washing away the cuttings, a jar-weight in the vicinity of the bit slidably associated in lost-motion relation to a part of the fluid-conducting means which is of constant length throughout the range of the jar-weight's lost-motion movement, and means other than the fluid-conducting means for actuating said jar-weight.

16. Well drilling apparatus comprising a bit, a pressure-fluid motor in the vicinity of the bit and constituting the mounting and driving means therefor, means extending from the top of the well to the motor for supplying pressure-fluid thereto, a jar-weight slidably associated in the vicinity of the motor in lost-motion relation to a part of the assembly which is of constant length throughout the length of the jar-weight's range of lost-motion movement, and means extending into the well and having connection to the jar-weight for raising and lowering the assembly and for actuating the jar-weight.

25 17. Well drilling apparatus comprising a plurality of bits each journaled for rotation on a non-vertical axis, a mounting common to said bits, and fluid-actuated means interposed operatively between the bits and the mounting for driving the bits and discharging the fluid adjacent the bits for washing the cuttings to the top of the well.

18. Well drilling apparatus comprising a plurality of bits each journaled for rotation on a non-vertical axis, a mounting common to said bits, and fluid-actuated means interposed operatively between each bit and the mounting for driving the bits and discharging the fluid in the vicinity of the bits for washing the cuttings to the top of the well, the bit assembly being so constructed and arranged as to drill an approximately round hole.

CLYDE E. BANNISTER.
